(57) **CLAIM**

The ornamental design for a bottle, as shown and described.

DESCRIPTION

FIG. 1 is an isometric view of a bottle, showing my new design;

FIG. 2 is a front elevational view thereof, the back view being identical;

FIG. 3 is a right side elevational view thereof, the left view being identical;

FIG. 4 is a top view thereof, enlarged to show detail;

FIG. 5 is a bottom view thereof, enlarged to show detail;

FIG. 6 is a front elevational view thereof, with the cap removed to show features which are not apparent in the other views, the back view being identical;

FIG. 7 is a right side elevational view thereof with the cap removed to show details which are not apparent in the other views, the left view being identical;

FIG. 8 is an isometric exploded view of the bottle of FIG. 1; and,

FIG. 9 is another isometric exploded view of the bottle of FIG. 1.

The broken lines show portions of the bottle which form no part of the claimed design.
